UNITED STATES PATENT OFFICE.

CARL E. PEARSON, OF LANSING, MICHIGAN.

BATTERY-CHARGING UNIT FOR INTERNAL-COMBUSTION ENGINES.

1,319,897.

Specification of Letters Patent. Patented Oct. 28, 1919.

Application filed April 16, 1917. Serial No. 162,299.

To all whom it may concern:

Be it known that I, CARL E. PEARSON, citizen of the United States, residing at Lansing, county of Ingham, State of Michigan, have invented a certain new and useful Improvement in Battery-Charging Units for Internal-Combustion Engines, and declare the following to be a full, clear, and exact description of the same, such as will enable others skilled in the art to which it pertains to make and use the same, reference being had to the accompanying drawings, which form a part of this specification.

My invention relates to a battery charging unit for internal combustion engines and an object of my improvements is to provide in such an apparatus for making and breaking the circuit at the proper time without employing complicated and delicate apparatus.

I secure this object in the device illustrated in the accompanying drawing in which:

The figure is an elevation partly in section of an apparatus embodying my invention, the circuit being shown diagrammatically.

a is a dynamo having a shaft *a*² upon which, near its bearing, is the circular flange *a*⁴. Beyond said flange the shaft is screw-threaded, as indicated at *a*³. *c* indicates a sleeve which is rigidly secured to the shaft of the engine (not shown). *c*² is a circular flange upon the end of the sleeve *c*. This flange is provided with apertures *c*³ near its periphery. *b* is a sleeve upon the shaft *a*² and having internal screw threads engaging the screw threads *a*³. *b*² is a circular flange coaxial with the flange *c*² and of about the same diameter and parallel thereto. *b*³ are pins rigidly secured to and extending at right angles from the face of the flange *b*² and passing loosely through the peripheral aperture *c*³ in the flange *c*². *b*⁴ is a flange upon the end of the sleeve *b* adjacent to the flange *a*⁴.

d is the storage battery. *e* *e*² *e*³ are the conducting wires forming part of the circuit through the battery *d* and dynamo *a*. *f* *f*² are the binding posts on said dynamo. *g* is a binding post carrying one of two contact points *h*. *i* is a flexible tongue secured at one end to the post *j* carrying the other of the contact points *h* and extending into the line of travel of the flange *b*⁴ of the

sleeve *b* for the purpose hereinafter described.

The operation of the above described device is as follows:

When the engine is running at normal speed it rotates the armature of the dynamo *a* and produces a current for charging the battery *d*. When the engine is stopped, or its speed falls so low that the voltage produced by the dynamo is less than the voltage of the battery *d*, a reverse current is sent through the dynamo and the latter is thereby driven as a motor running ahead of the engine and therefore acting through the screw threads *a*³ upon the sleeve *b* to force said sleeve away from the dynamo, its flange *b*⁴ coming against the tongue *i* and separating the contact points *h* and breaking the circuit. When the speed of the engine again increases and attains a sufficient rate to charge the battery, the sleeve *b* is carried back to its original position, the flange *b*⁴ contacting the flange *a*⁴ and the engine again driving the dynamo. As soon as the flange *b*⁴ is separated from the tongue *i* the points *h* are brought in contact by the resiliency of said tongue and the circuit through the battery and dynamo is again complete.

The charging current is indicated by the single headed arrows *E*, the current driving the dynamo as a motor is indicated in direction by the triple headed arrows *e*².

What I claim is:

The combination of an engine of variable speed, having a main shaft, a dynamo provided with a shaft axially in line with the engine shaft, a storage battery, said dynamo and battery being included in a common circuit, a make-and-break device in said circuit, one of said shafts being screw-threaded, a sleeve having internal screw threads upon said shaft, means engaging said sleeve with the other shaft so as to prevent relative angular movement but to permit a relative sliding movement in the direction longitudinal of the axis, and means whereby the movement of said sleeve longitudinally upon its shaft shall actuate said make-and-break device, substantially as and for the purpose described.

In testimony whereof, I sign this specification.

CARL E. PEARSON.
